UNITED STATES PATENT OFFICE.

ERNEST KLOPFSTEIN, OF CHICAGO, ILLINOIS, ASSIGNOR TO NORTH WESTERN ART SHADE CO., A CORPORATION OF ILLINOIS.

DESIGN FOR A LAMP BASE.

Application filed June 29, 1928. Serial No. 27,318. Term of patent 3½ years.

To all whom it may concern:

Be it known that I, ERNEST KLOPFSTEIN, a citizen of the United States, residing in Chicago, county of Cook, and State of Illinois, have invented a new, original, and ornamental Design for a Lamp Base, of which the following is a specification, reference being had to the accompanying drawing, forming part thereof.

In the drawing:

I claim:

The ornamental design for a lamp base, as shown.

ERNEST KLOPFSTEIN.
